UNITED STATES PATENT OFFICE.

JOHN M. HOLDA, OF CHICAGO, ILLINOIS.

LOCK.

Application filed July 28, 1924. Serial No. 728,533.

To all whom it may concern:

Be it known that I, JOHN M. HOLDA, citizen of the United States, residing at Chicago, in the county of Cook and State of Illinois, have invented certain new and useful Improvements in Locks, of which the following is a specification.

This invention relates generally to locks, having more particular reference to a lock whose bolt is arranged for retraction by a push button, the invention having for an object the provision of a novel lock of this sort, a further object of the invention relating to the provision of a novel arrangement of parts in which the device for holding the bolt retracted is utilized also to retain it in locking position.

For further comprehension of the invention, and of the objects and advantages thereof, reference will be had to the following description and accompanying drawing, and to the appended claims in which the various novel features of the invention are more particularly set forth.

Fig. 1 of the drawing is a longitudinal vertical sectional view of my improved lock, this view being taken on the line 1—1 of Fig. 2, the lock being here shown as applied to an automobile door.

Fig. 2 is a transverse sectional view taken on the line 2—2 of Fig. 1.

Fig. 3 is a fragmentary longitudinal sectional view taken on the line 3—3 of Fig. 2.

Fig. 4 is a face view showing my improved lock applied to a gate.

As here shown my improved lock comprises the rectangular casing which is adapted to be attached in any ordinary manner upon the door to be locked. Extending horizontally in this casing, a short distance from the bottom thereof, is a partition 11 from which depends a guide block 12 through which the bolt 13 extends slidably, this bolt projecting at one end through a suitable aperture in the end adjacent wall of the casing to engage keeper elements such as indicated at 14. The bolt has pivotally attached to its inner or rear end a link 16 which is pivotally attached at one end to the lower end of a lever 17 that extends obliquely in the casing and has pivotally attached to its other end a plunger pin 18 extending downward through an aperture 19 in the top wall of the casing. The pin has a head 18' on its lower end, the aperture 19 being countersunk on the top side

to allow the head 18' to enter partially therein. The aperture 19 is of sufficient size to permit of slight swinging movement of the pin as the latter moves with the lever 17. The lever 17 is suitably fulcrumed in the casing between its ends as at 20. Connected at one end to this lever, below its fulcrum point, and at the other end to the casing 10, is a coiled tension spring 22 which acts to normally urge the bolt 13 to locking position.

The bolt is positively retained against retraction by means of a vertical bar 25 which is slidably guided in the casing 10 and has at its upper end a lateral projection or stud 26 which engages in a vertical offset 27 from one end of a longitudinal groove 28 in one face of the bolt, the bar 25 being held in position with the stud engaged in this offset by means of a flat spring 29 connected at one end to the casing 10 and engaging at its other end under a lip 30 projected from one side of the bar. Pivoted a short distance from its upper end as 33 to the lower end of the bar 25 is a latch or dog 34 whose other end projects upward through a slot 35 in the top wall of the casing, the upper end of this dog being normally positioned some distance below the bottom face of the bolt 13. The bar 25 as will be apparent, holds the bolt against retraction until the dog 34 is pushed upward to bring the stud or projection 26 on the bar into registry with the groove 28 when the bolt may be retracted by pushing downward on the pin 18. When the bar 25 is in raised position the upper end of the dog 34 is in close adjacency to the top of the bolt 13, and may be caused to bite against the said bolt, to retain the latter retracted, by swinging the dog to an approximately vertical position. The partition element 11 has an aperture 37 in the bottom thereof to receive the end of the dog 34.

In Fig. 4 I have shown the invention applied to a gate, indicated generally at 40, the post 41 being provided with a keeper member 14' to receive the bolt.

Having thus described my invention, what I claim as new and desire to protect by Letters Patent of the United States is as follows:

1. A lock comprising a casing, a bolt slideable therein, means for retracting said bolt, said bolt being formed on one face with a longitudinal groove having a vertical offset at one end, a bar slideable in the casing trans-

versely to the said bolt and having at its lower end a projection normally engaging in said offset from said groove to hold the bolt against retraction, and a dog pivoted 5 to said bar and projecting at one end through the casing and forming the medium through which the said bar may be moved to bring the said projection thereon into registry with the longitudinal portion of 10 said groove, said dog being arranged to grip the said bolt by swinging movement of the dog when in depressed position.

2. A lock comprising a casing, a bolt slideable therein, means for retracting said bolt, 15 said bolt being formed on one face with a longitudinal groove having a vertical offset at one end, a bar slideable in the casing transversely to the said bolt and having at its

lower end a projection normally engaging in said offset from said groove to hold the bolt 20 against retraction, and a dog pivoted to said bar and projecting at one end through the casing and forming the medium through which the said bar may be moved to bring the said projection therein into registry with 25 the longitudinal portion of said groove, said dog being arranged to grip the said bolt by swinging movement of the dog when in depressed position, and a spring engaged with said bar and normally retaining the latter in 30 position with the projection thereon engaged in said offset from said groove.

In testimony whereof I have affixed my signature.

JOHN M. HOLDA.
